UNITED STATES PATENT OFFICE

2,508,111

PROTRACTOR

Richard R. Hassell, Cranston, R. I.

Application October 9, 1945, Serial No. 621,195

5 Claims. (Cl. 33—102)

1

This invention relates to a protractor.

In the use of protractors, when it is necessary to turn the protractor over from side to side, it is necessary to reset the protractor if any angle other than 90° is desired. It also is often necessary to spend considerable time centralizing the blade with reference to the body of the protractor, and further, the blade of a protractor is usually not rotatable with reference to the body throughout 360°.

One of the objects of this invention is to provide a protractor which is reversible from side to side without the necessity of resetting the blade in the body.

Another object of this invention is to mount the blade-carrying member in the body through a center bearing which will permit relative rotation between the blade and the body throughout 360°.

Another object of this invention is to so arrange the construction of the relatively moving parts that should the protractor be accidentally dropped, it will be sufficiently well supported so that breakage will be unlikely.

Another object of the invention is to provide an arrangement so that the blade will be very easily centered and adjusted in the member which carries it.

With these and other objects in view, the invention consists of certain novel features of construction, as will be more fully described and particularly pointed out in the appended claims.

In the accompanying drawings:

Fig. 1 is an elevation showing the protractor and illustrating in dotted lines a relatively different position of the blade with reference to the body.

Fig. 2 is a section on line 2—2 of Fig. 1.

Fig. 3 is an exploded view illustrating two parts of the body with the rotary member between, all in separated relation one from the other.

Fig. 4 is an edge view of the rule-carrying member and securing screw which fits therein, showing the slot for the rule.

In proceeding with this invention, I provide a body member in two parts, so arranged that when assembled a center bearing is provided with a radial space in all directions from this center bearing. I also provide between the parts a rule-carrying member which may swing about the center bearing through 360°, this member being slotted for the reception of a rule which may pass between the two sections or parts of the body member as relative rotation occurs.

With reference to the drawings, the body mem-

2

ber is designated generally 10 and consists of a front part or section 11 and a rear part or section 12. These sections are each generally circular with a base extending outwardly from the circle to provide a straight edge 13 on the part 11 and 14 on the part 12, and in this general shape, these parts are duplicates. The front part 11 is provided with a center bearing 15 with an annular recess 16 surrounding the same, the bearing 15 being held in position from the outer periphery 17 of this member 11 by means of U-shaped arms 18 extending from the outer periphery of the member 11 to this center bearing.

The inner part of section 12 is provided with a center recess 19 of the same diameter as the center bearing 15, so as to receive this center bearing 15 and provide a close peripheral fit thereof and also by reason of abutting against the bottom of the recess 19 the two parts or sections 11 and 12 are held in a desired spaced relation one from the other. A larger recess 20 is also provided in this member 12 which is circular and concentric with the recess 19. Recess 20 is usually the same size as the recess 16 in the front member 11, although it need not necessarily be so. A center opening 21 is provided in the member 12 through which a securing bolt 22 passes to have engagement with the threaded opening 23 in the bearing 15 so as to draw the two members 11 and 12 into snug engagement. A pin 24 extends into openings 25 in the member 12 and 26 in the member 11 so as to prevent relative rotation of these members about the axis of the bearing 15 in its recess 19.

The rule-carrying member is designated 27 and consists of a disc having a front portion 28 and a rear portion 29 with an outwardly extending fin 30 between the two. Portions 28 and 29 are usually in the same diameter and fit respectively the recesses 16 and 20 in the parts or sections 11 and 12. An opening 31 is provided in the member 27 so as to receive the bearing 15 and rotably mount the same thereon. The fin 30 extends outwardly between the members 11 and 12 as shown more clearly in Fig. 2.

Along one sector of the disc 27 I provide a slot 33 which extends inwardly to a point just short of the opening 31 and thus this fin is absent along the arc of the member 27 where the slot occurs. A rule 34 of a thickness substantially the thickness of the fin 30 is placed in the slot 33 and is provided with a groove 35, this groove receiving a binding screw 36 which is carried by this member 27 and is so shaped at its inner end as to enter the groove 35 and bind the rule in the member

27. The groove is so arranged that the edge of the rule abuts snugly against the edge 38 at the bottom of the slot so as to fix the rule in definite position with relation to the member 27 along the center axis of the rule. This securing and finding member 36 will pass beneath the arms 18 as the member 27 is rotated through 360° while the rule 34 in passing from its position shown in Fig. 1 to the position shown in dot-dashed lines in Fig. 1 will enter the space between the members 11 and 12 which was occupied by the fin 30 when the rule is in a position to align with the straight edges 13 and 14.

By reason of the construction above described, it will be plain that the member 27 may rotate through 360° carrying the rule 34 with it so as to align the rule at any angle with reference to the straight edges 13 and 14. This angle may be readily determined by reason of graduations 39 on the face of the member 27 cooperating with a datum line 40 on the edge of the body member 10.

By reason of the fin filling the space between the members, should the protractor be dropped, the spaced edges between the sections or parts of the body member will be well supported and will be unlikely to break. The center bearing affords efficient construction from a manufacturing standpoint while also well centering the rotary blade for operation. Sufficient friction will be provided by adjustment of the member 22 so as to maintain the rule in any adjusted position to which it is moved.

I claim:

1. A protractor comprising a body member formed in two sections, one section comprising an outer portion and a center bearing, bridging arms connecting the outer portion and center bearing and holding the same spaced to provide an annular recess surrounding said bearing, a rule carrying member sandwiched between said sections and having an opening receiving said bearing and rotatably mounted thereon, a rule lock on said carrying member extending into said annular recess and of a dimension to pass under 45

said bridging arms whereby said members may be relatively rotated through 360 degrees.

2. A protractor as in claim 1 wherein said rule lock extends parallel to the axis of said bearing.

3. A protractor as in claim 1 wherein said sections are locked against relative rotation.

4. A protractor as in claim 1 wherein said sections are spaced and said carrying member has a fin extending into said space.

10 5. A protractor comprising a body member formed of two sections each of generally circular form with a tangential straight edge, one section having a socket in its inner surface with a bottom wall, the other section having a surrounding portion and a center bearing, bridging arms connecting the outer portion and center bearing and holding the same spaced to provide an annular recess surrounding said bearing, said bearing extending into said socket and engaging said bottom wall to space said sections, a rule carrying member having a fin extending between said sections and an opening receiving said bearing and rotatably mounted thereon, said carrying member being provided with a slot in the plane with 15 said fin to receive a rule therein, a rule in said slot in a plane with said fin, a lock at right angles to said plane located to extend into said annular recess and of a dimension to pass under said bridging arms whereby said members with a rule held in the carrying member may be rotated 360 degrees, and means to draw said sections toward each other to lock the members in a desired position.
